NONREFILLABLE BOTTLE TOP

Richard Voltolini, New York, N. Y.

Application February 14, 1941, Serial No. 378,905

6 Claims. (Cl. 215—25)

This invention relates to new and useful improvements in a non-refillable bottle top.

The invention has for an object the construction of a bottle top which is characterized by an annular member for engaging into the neck of a bottle and a cup-shaped member mounted on said annular member and extending further into the neck of the bottle, and associated with certain additional mechanism for preventing the refilling of the bottle.

Still further invention proposed the provision of a valve within the cup-shaped member and cooperative with said valve seat for assisting in preventing the refilling of the bottle.

Another object resides in the provision of a cap for the bottle adapted to be sealed thereon and having an opening, and a hollow tubular shield being mounted on the cap over said opening and associated with a valve head in a particular manner cooperative with the wall of the cap for assisting in preventing the refilling of the bottle.

Still further the invention proposes a novel construction whereby the two valves mentioned previously are connected together so that one assists the operation of the other in a novel manner.

For further comprehension of the invention, and of the objects and advantages thereof, reference will be had to the following description and accompanying drawings, and to the appended claims in which the various features of the invention are more particularly set forth.

In the accompanying drawing forming a material part of this disclosure:

Fig. 1 is a perspective view of a non-refillable bottle top constructed according to this invention but illustrated without the slotted top cap.

Fig. 2 is a vertical sectional view of a portion of Fig. 1 illustrated with the slotted top cap.

Fig. 3 is a horizontal sectional view taken on the line 3—3 of Fig. 2.

Fig. 4 is a horizontal sectional view taken on the line 4—4 of Fig. 2.

Fig. 5 is a view similar to Fig. 2 but showing the positions of the parts when the bottle is inverted during the pouring out of the liquid therein.

Fig. 6 is a fragmentary sectional view similar to Fig. 2 but illustrating a modified form of the invention.

Fig. 7 is an inverted view of the device shown in Fig. 6.

Fig. 8 is an enlarged vertical sectional view of a portion of Fig. 6.

Fig. 9 is a horizontal sectional view taken on the line 9—9 of Fig. 8.

The non-refillable bottle top, according to this invention, includes an annular member 10 for engagement into the neck 11 of a bottle. A cup-shaped member 12 is mounted on the member 10 and extends further into the neck 11 and is formed with a rounded bottom end forming a valve seat 12^a having a small central opening.

10 A ball valve 13 is arranged within the member 12 and is cooperative with the valve seat 12^a for closing the small opening. A cap 14 is provided for the bottle and is sealed thereon by sealing material 15. This material may be wax or other sealing material. A hollow tubular shell 16 is mounted on the cap 14. The cap 14 is provided with an opening 17 arranged coaxially of the hollow tubular shell 16. A valve head 18 is mounted within the shell 16 and is adapted to rest on the top face of the cap 14 to seal the opening 17.

The annular member 10 preferably should be of cork material. The cup-shaped member 12 may be of sheet aluminum or other material. At its top edge it is secured to the annular member 10.

The cap 14 is provided with threads 14^a by which it is threadedly engaged on the neck of the bottle. The hollow tubular shell 16 is welded, soldered or in any other manner secured to the peripheral edge of the top wall of the cap 14. The valve head 18 consists of a hollow rubber guard member 18^a filled and weighted with a glass ball 18' and having a separate metallic bottom wall 18^b adapted to rest on the top wall of the cap 14 over the opening 17 for closing the opening. The hollow rubber member 18^a is formed with a plurality of serrations 18^c insuring the passage of liquid through the openings thereof in all positions of the valve head 18. The upper end of the shell 16 is closed by means of a cap 16^a welded in position thereon and which is formed with a reduced portion 16^b through which the liquid may be poured.

45 A slotted top cap 16^x is welded over the reduced portion 16^b. The top cap 16^x has a plurality of slots 16^y through which the liquid may pass. A projection 18^x from the wall 18^b extends through the opening 17 and prevents the valve 13 from closing said opening 17.

The operation of the device is as follows:

When the bottle is top side up the parts will assume the positions as shown in Fig. 2. In this condition it will be impossible to refill the bottle since both the valves 13 and 18 are engaged upon

their valve seats. The bottle may be emptied by tilting the top end downwards as shown in Fig. 5. In this condition the contents of the bottle may pass through the opening in the cup-shaped member 12, then through the annular member 10, through the opening 17, around the valve head 18, between the serrations 18^c, and finally out from the reduced end 16^a and the slots 16^y of the cap 16^x. The cap 16^x prevents tampering with the valves of the device.

In Figs. 6 to 9 a modification of the invention has been disclosed which distinguishes from the prior form in several respects. According to this form there is a valve head 18 co-operative with the opening 17 of the shell 14. This valve head 18 includes a hollow rubber member 18^a filled and weighted with a glass ball 18' and formed with a plurality of radial serrations 18^c. These serrations are so arranged that in all positions of the valve head it is possible for fluid to pass through the openings of the serrations and out from the reduced end 16^a of the shell 16. A rod 20 is connected coaxially with the separate metallic plate 18^b of the valve head 18. This rod 20 engages and supports the valve 13' which is co-operative with the valve seat 12^a.

A feature of this invention resides in the fact that the valve 13' is slidably resiliently mounted upon the lower end of the rod 20. In this construction the weight of the valve head 18 when in position across the opening 17 acts to resiliently urge the valve 13' in position upon its valve seat 12^a to close the opening formed in the bottom end of the valve seat cage 12. To accomplish this construction the valve 13' is formed with an inwardly extended opening 21 into which the bottom end of the rod 20 is slidably engaged. A means is provided for slidably holding the valve 13' in position upon the end of the rod 20. The rod 20 is formed with a radially extending pin 22 which engages a U-shaped cutout 23 formed in the side wall of the opening 21. This U-shaped opening 23 is characterized by a long arm 23^a which connects with the exterior of the valve 13' and which at its bottom continues into a short transverse intermediate arm 23^b which in turn connects with a short vertical arm 23^c. When engaging the valve 13' upon the end of the rod 20 the pin 22 is first passed through the arm 23^a until it reaches a position adjacent the intermediate transverse arm 23^b and then the rod 20 is twisted to align the pin 22 with the short vertical arm 23^c. During normal operation this short vertical arm 23^c is adapted to house the pin 22 to permit longitudinal movement of the valve 13' with relation to the rod 20.

An expansion spring 24 is mounted within the bottom of the opening 21 and operates between the bottom wall of this opening and the bottom end of the rod 20 for urging the valve 13' into an extended position with relation to the rod 20. In this position the pin 22 will bear against the top end of the short vertical arm 23^c of the U-shaped cutout 23 to limit the complete disengagement of the valve 13' from the end of the rod 20.

The operation of this form of the invention is similar to that described in connection with the previous form of the invention and differs therefrom by the fact that the weight of the valve head 18 acts to more rigidly urge the valve 13' in position upon the valve seat 12^a to more positively seal the opening in the bottom end of the valve cage 12. When the valves are in their open positions as shown in Fig. 7 the distance between the metallic plate 18^b and the valve 13' will be greater

than the distance between the opening 17 and the opening in the bottom end of the valve cage 12 due to the fact that the spring 24 will urge the valve 13' into an extended position with relation to the end of the rod 20. However, when the bottle is again tilted to its normal position as shown in Fig. 6 and the valve head 18 assumes its normal position across the opening 17, the weight thereof will act to compress the spring 24 as shown in Fig. 8 to urge the valve 13' further on to the end of the rod 20 and so seat the valve 13' upon the valve seat 12^a. The spring 24 is comparatively weak and the weight of the valve head 18 is sufficient to compress the same for the purpose hereinabove outlined. In other respects this form of the invention is similar to that previously described, and like reference numerals are used to identify like parts in each of the several views.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

30 1. A non-refillable bottle top having a cap formed with a central opening in its top wall and engaged upon the neck of a bottle with a cup-shaped member formed with a rounded bottom forming a valve seat having a small central opening projected into said neck and a tubular shell having a reduced top discharge opening having its bottom edge securely attached to the peripheral edge of said top wall, a weighted valve having a flat bottom side resting on the top face of the top wall of said cap for closing said opening in said top wall, a ball valve in said cup-shaped member engageable upon said valve seat, and a rod having its top end securely attached to the bottom face of said weighted valve and its bottom end projected through said opening in said top wall and into said cup-shaped member, said ball valve being resiliently mounted upon the bottom end of said rod to insure its being seated upon said valve seat when said weighted valve rests upon the top face of said top wall.

2. A non-refillable bottle top having a cap formed with a central opening in its top wall and engaged upon the neck of a bottle with a cup-shaped member formed with a rounded bottom forming a valve seat having a small central opening projected into said neck and a tubular shell having a reduced top discharge opening having its bottom edge securely attached to the peripheral edge of said top wall, a weighted valve having a flat bottom side resting on the top face of the top wall of said cap for closing said opening in said top wall, a ball valve in said cup-shaped member engageable upon said valve seat, and a rod having its top end securely attached to the bottom face of said weighted valve and its bottom end projected through said opening in said top wall and into said cup-shaped member, said ball valve being resiliently mounted upon the bottom end of said rod to insure its being seated upon said valve seat when said weighted valve rests upon the top face of said top wall, said rod being of a diameter substantially less than the diameter of said opening in said top wall so as not to interfere with the passage of liquid through said opening.

3. A non-refillable bottle top having a cap formed with a central opening in its top wall and engaged upon the neck of a bottle with a cup-shaped member formed with a rounded bottom forming a valve seat having a small central opening projected into said neck and a tubular shell having a reduced top discharge opening having its bottom edge securely attached to the peripheral edge of said top wall, a weighted valve having a flat bottom side resting on the top face of the top wall of said cap for closing said opening in said top wall, a ball valve in said cup-shaped member engageable upon said valve seat, and a rod having its top end securely attached to the bottom face of said weighted valve and its bottom end projected through said opening in said top wall and into said cup-shaped member, said ball valve being resiliently mounted upon the bottom end of said rod to insure its being seated upon said valve seat when said weighted valve rests upon the top face of said top wall, said rod having its bottom end slidably extended partially into an opening extended diametrically in from one side of said ball valve, said resilient mounting, comprising an expansion spring operating between the bottom wall of the opening in said ball valve and the bottom end of said rod.

4. A non-refillable bottle top having a cap formed with a central opening in its top wall and engaged upon the neck of a bottle with a cup-shaped member formed with a rounded bottom forming a valve seat having a small central opening projected into said neck and a tubular shell having a reduced top discharge opening having its bottom edge securely attached to the peripheral edge of said top wall, a weighted valve having a flat bottom side resting on the top face of the top wall of said cap for closing said opening in said top wall, a ball valve in said cup-shaped member engageable upon said valve seat, and a rod having its top end securely attached to the bottom face of said weighted valve and its bottom end projected through said opening in said top wall and into said cup-shaped member, said ball valve being resiliently mounted upon the bottom end of said rod to insure its being seated upon said valve seat when said weighted valve rests upon the top face of said top wall, said rod having its bottom end slidably extended partially into an opening extended diametrically in from one side of said ball valve, said resilient mounting, comprising an expansion spring operating between the bottom wall of the opening in said ball valve and the bottom end of said rod, said spring being weak enabling the weight of said weighted valve to compress the same when said ball valve is on said valve seat enabling said weighted valve to seat itself upon the top face of said top wall.

5. A non-refillable bottle top having a cap formed with a central opening in its top wall and engaged upon the neck of a bottle with a cup-shaped member formed with a rounded bottom forming a valve seat having a small central opening projected into said neck and a tubular

shell having a reduced top discharge opening having its bottom edge securely attached to the peripheral edge of said top wall, a weighted valve having a flat bottom side resting on the top face of the top wall of said cap for closing said opening in said top wall, a ball valve in said cup-shaped member engageable upon said valve seat, and a rod having its top end securely attached to the bottom face of said weighted valve and its bottom end projected through said opening in said top wall and into said cup-shaped member, said ball valve being resiliently mounted upon the bottom end of said rod to insure its being seated upon said valve seat when said weighted valve rests upon the top face of said top wall, said rod having its bottom end slidably extended partially into an opening extended diametrically in from one side of said ball valve, said resilient mounting, comprising an expansion spring operating between the bottom wall of the opening in said ball valve and the bottom end of said rod, and means limiting relative movement between said ball valve and said rod to insure the seating of said ball valve on said valve seat when said weighted valve is resting on said top wall and movement of said ball valve on said valve seat when said weighted valve moves off said top wall.

6. A non-refillable bottle top having a cap formed with a central opening in its top wall and engaged upon the neck of a bottle with a cup-shaped member formed with a rounded bottom forming a valve seat having a small central opening projected into said neck and a tubular shell having a reduced top discharge opening having its bottom edge securely attached to the peripheral edge of said top wall, a weighted valve having a flat bottom side resting on the top face of the top wall of said cap for closing said opening in said top wall, a ball valve in said cup-shaped member engageable upon said valve seat, and a rod having its top end securely attached to the bottom face of said weighted valve and its bottom end projected through said opening in said top wall and into said cup-shaped member, said ball valve being resiliently mounted upon the bottom end of said rod to insure its being seated upon said valve seat when said weighted valve rests upon the top face of said top wall, said rod having its bottom end slidably extended partially into an opening extended diametrically in from one side of said ball valve, said resilient mounting, comprising an expansion spring operating between the bottom wall of the opening in said ball valve and the bottom end of said rod, and means limiting relative movement between said ball valve and said rod to insure the seating of said ball valve on said valve seat when said weighted valve is resting on said top wall and movement of said ball valve on said valve seat when said weighted valve moves off said top wall, comprising a radial pin extending from said rod and engaging a radial slot formed along one side of the opening in said ball valve.
